RADIO TRANSMITTER

John Evans, Oaklyn, N. J., assignor to Radio Corporation of America, a corporation of Delaware

Application November 17, 1936, Serial No. 111,183

2 Claims. (Cl. 179—171.5)

My invention relates to improvements in radio transmitters, and more specifically to a method of and means for efficiently modulating a radio frequency carrier over a wide band of frequencies.

5 The system of modulating radio transmitters, suggested by Heising, is known as a constant current modulating system. The essential characteristic of the Heising system is obtained by feeding the anode circuit of a modulator and 10 the anode circuit of an amplifier through an inductive reactor whose reactance is sufficiently high, throughout the useful signal frequency range, to insure a substantially constant current. This constant current is divided or proportioned 15 between the anode circuit of the modulator and the anode circuit of the amplifier, in accordance with the signal or modulation current.

While the Heising system of modulation is entirely satisfactory over a limited range of modulation frequencies, the constant current reactor becomes very inefficient when currents having a frequency range from a few cycles per second to several hundreds of thousands cycles per second are applied. The modulation frequencies 25 employed in high fidelity television transmission often cover a frequency range of a million or more cycles per second, and when such modulation frequencies are applied in the Heising modulation system, the losses become excessive. The 30 present invention contemplates a modulation system capable of efficiently handling large amounts of power at modulation frequencies of the order of a million or more cycles per second.

An object of my invention is to provide improved means for modulating a radio frequency carrier by signal currents covering a wide range of frequencies.

Another object is to provide improved means for applying signal currents to modulate an auxiliary carrier, rectifying the modulated auxiliary carrier currents, filtering the carrier currents, and applying the rectified currents, which are pulsating at signal modulation frequencies, to the anode circuit of a modulator which is coupled 45 to the main carrier frequency generator.

A further object is to provide a radio transmitter with means for modulating the auxiliary carrier, means for attenuating currents of one side band, and for passing currents of the auxiliary carrier and the other side band, the latter currents, after being rectified and after filtering the auxiliary carrier, becoming the source of anode currents of a modulator which is coupled to the main carrier frequency generator.

55 A still further object is to provide improved

means for modulating a carrier current, radiating the modulated carrier, and suppressing the carrier during periods of no modulation.

My invention may be best understood by reference to the accompanying drawing, in which Figure 1 is a schematic circuit diagram of one embodiment of my invention, and

Figure 2 is a circuit diagram illustrating a modification of the circuit of Fig. 1.

Referring to Fig. 1, a source of signal frequency current is represented by reference numeral 1. The signal frequency source 1 is connected to the resistance coupled amplifier 3, whose output circuit includes an anode current source 5 and a resistor 7. A connection is made 10 from a point intermediate the ends of the resistor 7 to a tuned circuit 9 which is connected to the anodes of a pair of push-pull modulator tubes 11, 13 which are preferably biased for Class C operation. The input circuit of the modulator tubes 11, 13 is connected to a source 15 of carrier frequency currents. The currents from source 15 will hereinafter be called the auxiliary carrier to distinguish from the normal carrier which will be described below. By way of example, the auxiliary carrier may be operated at a frequency of seven megacycles.

The tuned circuit 9 in the anode circuits of the push-pull tubes 11, 13 is suitably coupled to a second tuned circuit 17. Both tuned circuits 9, 17 are resonant to the frequency of the auxiliary carrier, and the mutual coupling M is adjusted to give the desired characteristics to thereby pass the modulated auxiliary carrier currents without attenuating the signal frequency components. A point 19 on the tuned circuit 17 is grounded. The terminals of the tuned circuit 17 are connected to a full wave rectifier 21.

The output of the rectifier 21 includes a filter which comprises an inductor 23 and a capacitor 25. The filter 23, 25 is adjusted to remove the auxiliary carrier ripple and preferably has a time constant of the order of the period of the auxiliary carrier. That is, $\frac{1}{4},000,000$ second for a 7 megacycle per second auxiliary carrier with a 45 half-wave rectifier, and $\frac{1}{4},000,000$ second for a full-wave rectifier.

The output of the rectifier is connected to the mid-point 27 of a circuit 29 which is resonant to currents of the main carrier frequency. The terminals of the resonant circuit are connected in push-pull relation to the anodes of a pair of modulator tubes 31, 33. The grid circuits of the modulator tubes 31, 33 are preferably biased for Class C operation and are connected to a gener- 55

- ator 35 of carrier frequency currents. The tuned anode circuit 29 is suitably coupled by mutual inductance M , or the like, to an antenna system 37.
- 5 The operation of the foregoing system is essentially as follows: The signal frequency currents, which may be derived from any source, such as a television scanning system, are amplified by the thermionic tube 3. The amplified currents vary the potential applied, through the tuned circuit 9, to the anodes of the push-pull modulator 11, 13. The auxiliary frequency carrier currents are impressed on the grid or input circuits of the modulators 11, 13, and subsequently transferred to the anode circuits of the modulators. Thus the currents of auxiliary carrier frequency are modulated by the signal frequency currents in accordance with the conventional theory of anode circuit modulation.
- 10 The modulated auxiliary carrier currents are transferred to the mutually coupled circuit 17, where the rectifier 21 rectifies the modulated auxiliary currents, and thereby produces pulsating unidirectional currents of twice the signal frequency. The pulsating currents are impressed on the filter 23, 25, which has a time constant of the proper characteristic to smooth out the pulsating currents and deliver a steady current upon which is superimposed the original signal frequency current. These steady and varying currents become not only the source of anode current for the push-pull modulators 31, 33, but also the modulation current for these tubes 31, 33. The currents from the main carrier frequency generator 35 are impressed on the input circuits of the modulator tubes 31, 33.
- 15 The main carrier frequency currents are modulated by the rectified filtered currents, when both carrier and filtered currents are present in the anode circuits of the push-pull modulators 31, 33. The thus modulated carrier frequency currents are transferred from the resonant anode circuit 29, through the mutual coupling M , to the antenna circuit 37. Since the anode current for the modulators 31, 33 is a steady current which is varied by the signal frequency currents, it will be apparent that amplitude of the main carrier current will vary in proportion to the signal when signals are impressed on the source 1 in accordance with the foregoing description.
- 20 The above described method of modulation may be applied to a single side band transmitter, as indicated by the circuit diagram of Fig. 2. The signal frequency source 41 is connected to the input of an amplifier 43 which has an anode circuit comprising a source of anode current 45 and a resistor 47. The output of the amplifier 43 is impressed on a resonant circuit 49, which is connected to the anodes of push-pull modulator tubes 51, 53. The control grids of the modulator tubes are preferably biased for Class C operation and are connected to the auxiliary carrier frequency generator 55.
- 25 The resonant circuit 49 is mutually coupled to a second resonant circuit 57. The terminals of the second resonant circuit may be connected to the input of a band pass filter 59 through a balanced modulator 60, which may be omitted in accordance with a description which appears below. The output of the filter 59 includes a third resonant circuit 61 which is mutually coupled to a fourth resonant circuit 63. The fourth resonant circuit 63 is connected to a full-wave rectifier 65, 67. The output of the rectifiers 65, 67 is connected to a filter 69, 71, which is in turn con-

nected to the center tap of a push-pull transformer 73. The terminals of the push-pull transformer 73, which is preferably resonant to currents of the main carrier frequency, are connected to the anodes of a pair of push-pull thermionic modulators 75, 77. The input circuits of these tubes 75, 77 are preferably biased for Class C operation and are connected to the source 79 of the main carrier currents.

30 The push-pull transformer 73 is mutually coupled M to a second resonant push-pull transformer 81, which is connected to the input circuit of a power amplifier 83. The power amplifier is biased for Class B operation and comprised of suitable tubes 85, 87 which, if triodes, may be neutralized by capacitors 89, 91. Screen grid tubes may be used in place of neutralized triodes 85, 87. The anode circuit of power amplifier 83 is comprised of a tuned circuit 93, which is mutually coupled M to an antenna circuit 95.

35 The operation of the circuit of Fig. 2 is not greatly different from the circuit of Fig. 1. In the latter circuit both the auxiliary carrier and side band currents are impressed on the rectifier. In the present circuit (Fig. 2), the input to the balanced modulator includes two 7 megacycle voltages, one of which may be amplitude modulated. In the absence of modulation the two 7 megacycle voltages combine to produce a resultant 14 megacycle current which is not used since it is attenuated by the band pass filter 59. The relative amplitudes of the two 7 megacycle voltages are adjusted to reduce to a desired amplitude the 7 megacycle auxiliary carrier in the balanced modulator output.

40 When signal frequency modulation containing an alternating and a varying direct current component is applied, two operations are initiated. First, the average amplitude of the 7 megacycle carrier which is applied to the balanced modulator input through transformer 57 takes a value which is determined by the direct modulation component, so that the amplitude of 7 megacycle current in the modulator output takes a corresponding value; and, second, modulation frequency components are superimposed on the carrier output of the modulator corresponding to the alternating components of the signal frequency.

45 The band pass filter 59 is adjusted to attenuate currents of one side band, and to pass carrier and the other side band currents. These currents are rectified, and are filtered to remove, if necessary, any residual carrier ripple. The thus rectified and filtered currents comprise two components. There is a d-c component derived from the rectified and filtered 7 megacycle carrier, the amplitude of which is proportional to the average carrier amplitude, and there is also a signal frequency component corresponding to the original signal frequency. The output currents are sufficiently amplified to form the anode current source for the modulators 75, 77. The varying anode currents will transfer the main carrier currents in varying amplitudes, through the power amplifier 83, to the antenna circuit 95 from which modulated waves will be radiated. During periods of no signal, the amplitude of the radiated carrier will be determined by the value of the bias applied to the output tubes by the battery connected to the mid-point of transformer 81.

50 The purpose of the balanced modulator is to reduce the amplitude of both the main and the auxiliary carrier during periods of zero modulation. This produces an appreciable saving in the transmitter power consumption during "stand by".

by" periods. When the auxiliary carrier is so reduced by the balanced modulator the radiated carrier is likewise reduced since only a carrier of reduced amplitude and no side bands are impressed on the rectifiers 65 and 67, and the radio frequency amplifier tubes 75 and 77 are operated at reduced power.

In some installations, it may be desirable to radiate a carrier of constant average amplitude by omitting the balanced modulator 60 or the like, between the auxiliary modulators 51, 53 and the rectifiers 65, 67. The finally modulated carriers may be transmitted by radiation, by concentric lines, or any suitable transmission system. It should be understood that half-wave rectifiers may be used in place of full-wave rectifiers. The amount of filtering, between the rectifiers of the auxiliary carrier wave and the main modulators, is determined by the permissible amount of ripple. In general, the time constant of the filter is approximately equal to the time of one cycle of the auxiliary carrier if a half-wave rectifier is used, and to half the time of one cycle if a full-wave rectifier is employed.

While plate circuit modulation has been used with Class C modulators, by way of illustration, it will be obvious to those skilled in the art that my invention may be applied to grid modulation. If grid modulation is contemplated, I prefer to bias the modulators for Class B modulation. The so-called Class B and Class C modulation or amplification systems are well known to those skilled in the art and require no detailed descriptions.

I claim as my invention:

1. In combination, a source of signal frequency currents, a source of auxiliary carrier frequency currents, means for modulating the peak amplitude of said auxiliary currents in accordance with variations of said signal frequency currents and for simultaneously modulating the average amplitude of said auxiliary frequency currents in proportion to the average amplitude of said signal frequency currents, means including a balanced

modulator coupled to the output of said first mentioned modulating means for reducing the amplitude of said auxiliary carrier during periods of zero modulation, means coupled to the output of said balanced modulator for producing a rectified current having a direct current component proportional to the average amplitude of said modulated auxiliary carrier and an alternating current component proportional to changes in the peak amplitude of said auxiliary carrier, a source of main carrier frequency currents, and means for modulating said main carrier frequency currents in accordance with both components of said rectified current.

2. In combination, a source of signal frequency currents, a source of auxiliary carrier frequency currents, means for modulating the peak amplitude of said auxiliary currents in accordance with variations of said signal frequency currents and for simultaneously modulating the average amplitude of said auxiliary frequency currents in direct proportion to the average amplitude of said signal frequency currents, means including a balanced modulator coupled to the output of said first mentioned modulating means for reducing the amplitude of said auxiliary carrier during periods of zero modulation, a rectifier coupled to the output of said balanced modulator, a filter network connected with said rectifier for smoothing out amplitude variations occurring at the frequency of the rectified auxiliary carrier to produce a rectified current having a direct current component whose amplitude is proportional to the average amplitude of said modulated auxiliary carrier and an alternating current component whose amplitude is proportional to the peak amplitude of said auxiliary carrier, a source of main carrier frequency currents, and means for modulating said main carrier frequency currents in accordance with both of said components of said rectified current.

JOHN EVANS.
